UNITED STATES PATENT OFFICE

2,516,600

SNOW SWEeper RAILWAY CAR

Calvin W. Shipley, Munster, Ind., and Herman C. Van Eck, Chicago, Ill., assignors to O. F. Jordan Company, East Chicago, Ind., a corporation of Indiana

Application April 16, 1949, Serial No. 87,902

8 Claims. (Cl. 15—55)

1

This invention relates to improvements in snow sweeper railway cars and it consists of the matters hereinafter described and more particularly pointed out in the appended claims.

One of the objects of the invention is to provide a railway car for sweeping snow from zones along the running rails of a railway track and for directing the snow upwardly for entrainment into the air stream produced by the forward movement of the car, so that said snow becomes airborne by said stream and is thereafter directed rearwardly and outwardly from both sides of the car for disposal in zones along the track where the snow cannot interfere with train movement.

Another object of the invention is to provide in a car of this kind, an improved arrangement of air stream directional surfaces, whereby said stream is directed inwardly from opposite sides of the front end of the car to there join together at an entrainment space or zone and where the comminuted snow thrown upwardly and forwardly by the rotating brushes of the car, becomes airborne by said stream, which is then directed upwardly for division into portions, each turned outwardly from the sides of the car, for discharge.

A further object of the invention is to provide in a car of this kind, an improved arrangement of brush frames, one at each side of the snow entrainment space, which frames are mounted for movement from an operative position for sweeping snow from the running rail zones, to an inoperative position within the equipment lines of the car, for clearance purposes when the car is being moved between periods of snow sweeping use.

The above mentioned objects of the invention, together with others, as well as the advantages thereof, will more fully appear as the specification proceeds.

In the drawings:

Fig. 1 is a view in side elevation of a snow sweeper railway car embodying the preferred form of the invention with the sweeper brushes in the operative position.

Fig. 2 is a top plan view of the car appearing in Fig. 1.

Fig. 3 is a transverse vertical sectional view through the snow entrainment space or zone of the car, as taken on the line 3—3 and on a scale enlarged over that of Fig. 1, with one rotary brush shown in its operative position and with the other of the brushes shown in its inoperative position, as when the car is in transport between periods of use.

2

Fig. 4 is a perspective view of one of the frames for supporting one of the rotary brushes from the underframe of the car.

In general the improved car is of such construction that it can be equipped with trucks, couplers, draft gears, brakes and safety appliances required as standard in railway cars. Said improved car embodies a wheeled truck mounted underframe, that includes a center sill, end 10 sills and side sills, which in this instance stop short of what may be termed the snow sweeping and entrainment space or zone of the car, located between the opposed ends of the side sills and where both sides of the center sill are 15 exposed.

Said car, while it may carry its own motive equipment, is herein shown as constructed to be pushed forwardly as the leading car of a train of cars equipped with its own locomotive, 20 or to be pushed by a locomotive alone.

At the front end or deck of the car an enclosure for the operating personnel is located, which occupies about one-third the length of the car. This enclosure has a rounded front or 25 advance end, whereby as the car moves forwardly, said end causes the air stream to follow around opposite sides of the car and thence inwardly toward the center of the car. The rear end of this enclosure tapers at both sides rearwardly and inwardly to terminate as an upright trailing edge disposed in the center line of the center sill. This enclosure is provided with suitable doors and windows for access of the 30 screw and for clear vision at the front, the sides and the rear of the enclosure.

At the rear end of the deck of the car is a second enclosure of the same height as the first mentioned enclosure. Said second enclosure may contain certain equipment, such as air 35 tanks, auxiliary engine, generator, etc. It occupies about a third of the length of the car, its front end is of a V or wedge shape and includes side portions that extend outwardly and rearwardly from its leading edge, which is also disposed on the center line of the center sill.

The space or zone between said enclosures is an open one and constitutes a snow entrainment space or zone of the car.

Associated with the wedge shaped front end 50 of the rear enclosure is an air scoop having a transverse front or leading edge disposed below the center sill. This scoop inclines upwardly and rearwardly from said edge, with upper end portions thereof disposed upon opposite sides of the wedge shaped front of the rear enclosure. Extending between the leading margin of the scoop

and that part of the center sill above the same is a secondary wedge for giving a better controlled division for such snow as may be picked up by the advancing margin of the scoop and for directing it as two stream parts, onto the scoop and thus prevent packing of the snow under the center sill at this point.

At each side of the exposed part of the center sill, in advance of the leading margin of the scoop, an open frame is pivoted, which swings on an axis parallel the center sill. Each frame carries a rotary sweeper brush that is mounted on a shaft extending transversely of the car, which brush when driven, rotates in such a direction that when engaged in snow along the running rail zones, such snow is thrown or swept forwardly and upwardly into the air stream for entrainment therein to be airborne thereby and then directed upwardly and rearwardly and outwardly for gentle discharge at each side of the car.

Each of the brush frames has associated therewith a means operable by the crew in the front enclosure to swing the brush from its operative position mentioned to an inoperative position within the planes of the sides of the car as a whole so as to be out of the way when the car is in motion from one place of use to another.

Referring now in detail to that embodiment of the invention illustrated in the drawings, the improved snow sweeper car includes an underframe mounted on trucks that include the pairs of wheels 10-10 for a running engagement upon the rails 11-11 of a railway track. The frame includes a center sill 12 of hollow box-like construction, end sills 13-13 and front and rear side sill portions 14-15 which extend toward each other from the end sills, but are spaced apart at the mid portion of the car.

On the front end of the underframe is a decking 16 upon which is mounted a cab-like enclosure 17 for the operating crew, which enclosure is narrower than the decking, to leave portions of the decking at each side of the enclosure. The enclosure includes a top 18, a rounded front end 19, that merges at its ends into parallel side portions 20 and rearwardly of said side portions and forming continuations thereof, are rearwardly and inwardly extending wall portions 21 that meet as an upright trailing edge 22. In the front and in the side and wall portions of this structure are windows 23 and doors 24 by which the crew has a full vision forwardly, laterally and rearwardly, and by which doors the crew may enter and leave the cab-like structure.

On the rear end of the underframe a second cab-like structure 25 is located, in which may be located equipment, such as a compressed air tank 26 and an auxiliary engine and compressor and generator casing 27, which compressor to provide the compressed air for storage in the tank 26.

The cab-like structure 25, which has a substantially arrowhead shape, as appears in Fig. 2, includes a top 28, a back wall 29, side wall portions 30-30 that are parallel with the sides of the car as a whole and forwardly and inwardly extending side wall portions 31-31 that meet as an upright advancing or leading edge 32 disposed on the median line of the center sill 12. The leading edges 22 and 32 of said cab-like structures 17 and 25 are spaced apart longitudinally of the center sill to form a snow entrainment zone or space 33 best appearing in Fig. 1.

A running board 34 is disposed centrally of the

car and has end portions disposed upon the tops 18 and 28 of the structures 17 and 25 and this board bridges the zone or space 33. The rear end of the structure 17, as constituted by the walls 21 and edge 22, affords a streamline contour, whereby the air stream produced by the forward movement of the car is caused to enter the zone or area 33, along an inwardly sweeping path. This air stream will have a velocity approximating the speed of movement of the car, say of the order of from 25 to 35 M. P. H.

The rear end structure, as constituted by the walls 31 and edge 32, forms a wedge for splitting the before-mentioned air stream into two equal parts or substreams and directs each of the substreams rearwardly and outwardly for discharge at opposite sides of the structure, as indicated by the arrows in Fig. 2.

Associated with the structure just above mentioned is a means for deflecting the air stream upwardly, which means is in the form of an upwardly and rearwardly inclined air scoop 35. This scoop includes a leading edge 36 that extends transversely of the car and is located in a plane below that of the center sill and fairly close to the plane of the top of the running rails 11. Said scoop extends upwardly and rearwardly from this margin and terminates in a plane about midway between the top and the bottom of the rear ends of the walls 31-31. Thus, as will be best seen from Fig. 2, there are portions of the scoop disposed at each side of the walls 31-31 of the structure 25 and these scoop portions deflect the substreams of air upwardly, as they are deflected outwardly by said walls.

Between the front margin of the scoop and that portion of the center sill 12 above the same is a secondary wedge structure 37, which prevents packing of snow at this point by directing the same outwardly for an upward movement along the scoop toward the rear end thereof.

At each side of the center sill, within the zone or space 33 is located a means for picking up the snow in the zones along the running rails 11, for reducing the snow to a relatively fine or comminuted condition, and for throwing the snow forwardly and upwardly for entrainment into the air stream as it passes the zone 33. Said means includes a rectangular open frame 38, one of which appears in Fig. 4. Each frame includes a supporting shaft 39, which extends parallel with the center sill and which is journaled in brackets 40-40 carried by the center sill and extending downwardly and outwardly therefrom, as best appears in Fig. 3.

The frame 38 further includes a frame bar 41 spaced from but parallel with said shaft and a side bar 42 connecting said shaft and the first mentioned bar. A brush shaft 43 is arranged parallel with the side bar 42 and in turn is supported by the shaft 39 and frame bar 41. One end of the shaft 39 is bent to form a crank arm 44 arranged outwardly of but parallel with the frame bar 42.

Mounted on the shaft 43 for rotation is a circular brush 45, which includes a cylinder that is journaled on said shaft 43 and bristles radiating therefrom and arranged in groups or portions 45, 46 and 47 thereon. The bristles in the portion 45a are shorter than those in said brush portions 46 and 47 so that the brush as a whole is contoured to span a third or power rail 48, which appears in Fig. 2 when the car is in operation upon a third rail electrified railway system.

The brushes may be driven in any suitable manner and one way is to provide an individual motor 50 for each brush. This motor may be carried upon the bar 42 of the associated frame 38 and through a sprocket 51 and chain 52 drives a sprocket 53 journaled on the shaft 43 and suitably fixed to the associated brush cylinder. Power for the motors 50 may be generated by the equipment 27 and is controlled by the operator in the cab-like structure 17.

The brush frames 38 are shown in their lowered operative positions in Figs. 1 and 2 and in the left hand side of Fig. 3 and when in this position, project outwardly from the side contour of the car. However, when the car is moved from one place of operation to another, it is advisable that these frames be disposed in an inoperative position within said side contour of the car for clearance purposes and such a position is illustrated in the right hand side of Fig. 3.

For swinging each brush frame from one to the other of said positions an air cylinder 54 is provided. Both cylinders are disposed in the plane of the arms 44 for both frames 38 and these cylinders are pivotally attached at their upper ends to an upstanding bracket 55 on the center sill. Within each cylinder is a piston (not shown) to which is connected a piston rod 56 that slides through the bottom end of the respective cylinders and is pivotally connected to an associated arm 44.

Air for operating the cylinders and pistons is provided by suitable piping (not shown) from the air tank 26 and controlled by the operator in the cab-like closure 17. When air from the tank 26 is admitted to the upper end of the respective cylinder 55, the piston rod 56 thereof is projected outwardly and this swings or lowers the frame 38 downwardly to dispose the brush in the operative position. When such air is admitted to the lower end of the cylinder, this retracts the piston rods, which swings the frame to the inoperative position shown on the right hand side of Fig. 3. In this position, the brushes are disposed within the side contours of the car and afford the clearance required in transport.

In the operation of the car, assume that the car is being pushed by suitable motive power, say at about a speed of 30 miles per hour and that the brushes 45 are in the operative position and are being driven by their motors 50 in the direction of the arrow, Fig. 1.

In the rotation of the brushes, snow along the track rail zones is brushed or swept therefrom to be thrown forwardly and upwardly, in a somewhat comminuted or fluffy condition, into the air stream in the area 33 and wherein it is entrained in said stream to be airborne thereby. The airborne snow travels rearwardly with the air stream which is directed upwardly by the scoop and as it reaches the leading edge 32 of the wedge, the air stream is split centrally into portions which follow upwardly of the upper end of the scoop and are then deflected outwardly by the surfaces 34 for discharge from opposite sides of the car where it may fall in a gentle manner.

Because of the small volume of snow removed per lineal foot of track and the fine condition of such snow, together with the speed or velocity of the air stream, the snow will be entrained into the air stream and be carried to a discharge zone which will not affect train operation.

While in describing the invention we have referred in detail to the form, construction and ar-

rangement of the parts involved, the same is to be considered only in the illustrative sense and therefore we do not wish to be limited thereby except as may be specifically set forth in the appended claims.

We claim as our invention:

1. In a car for railway snow sweeper, a frame including a center sill and side sill portions at the front and rear ends of the car, means providing a forwardly facing air wedge on said center sill and the side sills at the rear end portions of the frame and including a forwardly facing leading edge, centrally of and above and below the center sill and including outwardly and rearwardly extending side deflecting surfaces, an air scoop associated with said wedge and including a transverse leading edge positioned below the leading edge for the wedge and a surface extending upwardly and rearwardly from said transverse edge and having upper end positions disposed upon opposite sides of the side surfaces of said air wedge, means mounted on the center sill and the side sills at the front end of the car and providing rearwardly and inwardly extending air current relieving surfaces that terminate in an upright trailing edge spaced forwardly of the leading edge of the air wedge.

2. A snow sweeper railway car embodying therein a wheeled frame, an air wedge on said frame and including an upright leading edge arranged substantially centrally thereof and side surfaces extending rearwardly and outwardly in opposite directions from said edge, an air scoop on said frame and having a horizontal leading edge arranged transversely of the car forwardly of the leading edge of the wedge and below said frame, and including a panel extending upwardly and rearwardly from said edge of the air scoop with upper end portions disposed laterally along each side surface of the air wedge, a cylindrical brush arranged in advance of said edge of the air scoop and having operative and inoperative positions, said brush when in said operative position extending across one of the rails of the track upon which the car may travel, a movable frame in which said brush is journaled for rotation, means connecting said movable frame to said wheeled frame for movement between said positions of the brush, means for imparting movement to said movable frame from one to the other of said positions for said brush, and power means for rotatively driving said brush when it is in the operative position.

3. A snow sweeper railway car embodying therein a wheeled frame, an air wedge on said frame and including an upright leading edge arranged substantially centrally thereof and side surfaces extending rearwardly and outwardly in opposite directions from said edge, an air scoop on said frame and having a horizontal leading edge arranged transversely of the car forwardly of the leading edge of the wedge and below said frame, and including a panel extending upwardly and rearwardly from said edge of the air scoop with upper end portions disposed laterally along each side surface of the air wedge, a cylindrical brush arranged in advance of said edge of the air scoop and having operative and inoperative positions, said brush when in said operative position extending across one of the rails of the track upon which the car may travel, a movable frame in which said brush is journaled for rotation, means connecting said movable frame to said wheeled frame for movement between said positions of the brush, means for imparting

movement to said movable frame from one to the other of said positions, power means for rotatively driving said brush when it is in the operative position, and means on said wheeled frame and spaced in advance of said brush and including at the rear thereof an upright trailing edge arranged substantially centrally of said frame and side surfaces extending forwardly and outwardly in opposite directions from said edge.

4. A snow sweeper railway car embodying therein a wheeled frame including a center sill, an air wedge on said frame and including an upright leading edge arranged centrally of said sill and side surfaces extending rearwardly and outwardly in opposite directions from said edge, an air scoop on said frame and having a horizontal leading edge arranged transversely of the car forwardly of the leading edge of the wedge and below said frame and including a panel extending upwardly and rearwardly from said edge of the air scoop with its upper end portions disposed laterally along each side surface of the air wedge, cylindrical brushes, arranged one on each side of the center sill in advance of said edge of the air scoop and each having an operative and inoperative position, each brush when in said operative position extending across a rail of the track upon which the car may travel, a movable frame in which each brush is journaled for rotation, means connecting each movable frame to said center sill for movement between said positions for the brush, means for imparting movement to each movable frame from one to the other of said positions, and power means for rotatively driving each brush of each movable frame when it is in the operative position.

5. A snow sweeper railway car embodying therein a wheeled frame, an air wedge on said frame and including an upright leading edge arranged substantially centrally thereof and side surfaces extending rearwardly and outwardly in opposite directions from said edge, an air scoop on said frame and having a horizontal leading edge arranged transversely of the car forwardly of the leading edge of the wedge and below said frame, and including a panel extending upwardly and rearwardly from said edge of the air scoop with upper end portions disposed laterally along each side surface of the air wedge, a cylindrical brush arranged in advance of said edge of the air scoop and having operative and inoperative positions, said brush when in said operative position extending across one of the rails of the track upon which the car may travel, a movable frame in which said brush is journaled for rotation, means connecting said movable frame to said wheeled frame for movement between said positions of the brush, means for imparting movement to said movable frame from one to the other of said positions, and power means carried on said movable frame and connected to said brush for rotatively driving the same when it is in its operative position.

6. A snow sweeper railway car embodying therein a wheeled frame including a center sill, an air wedge on said frame and including an upright leading edge arranged centrally thereof and side surfaces extending rearwardly and outwardly in opposite directions from said edge, an air scoop on said frame and having a horizontal leading edge arranged transversely of the car forwardly of the leading edge of the wedge and below said frame and including a panel extending upwardly and rearwardly from said edge of the air scoop with its upper end portions disposed

laterally along each side surface of the air wedge, a cylindrical brush arranged one on each side of the center sill in advance of said edge of the air scoop and each having an operative and inoperative position, each brush when in said operative position extending across a rail of the track upon which the car may travel, a movable frame in which each brush is journaled for rotation, means connecting each movable frame to said center sill for movement between said positions for the brush of each movable frame, means for imparting movement to each movable frame from one to the other of said positions, power means for rotatively driving each brush when it is in the operative position, an operator's cab mounted on the frame forwardly of said brush, and means to the rear of said cab and including an upright trailing edge arranged centrally of said frame and side surfaces that extend outwardly and forwardly of said edge, said edges being spaced longitudinally of the car.

7. A snow sweeper railway car embodying therein a wheeled frame including a center sill, an air wedge on said frame and including an upright leading edge rising from said center sill and side surfaces extending rearwardly and outwardly in opposite directions from said edge, an air scoop on said frame and having a horizontal leading edge arranged transversely of the car forwardly of the leading edge of the wedge and below said frame and including a panel extending upwardly and rearwardly from said edge of the air scoop with upper end portions disposed alongside each side surface of the air wedge, a cylindrical brush arranged in advance of said edge of the air scoop and having operative and inoperative positions, said brush when in said operative position extending across one of the rails of the track upon which the car may travel, a movable frame in which said brush is journaled for rotation, means carried by said center sill and including a shaft arranged parallel with said sill and providing a pivotal axis for said movable frame about which it may be swung from one to the other of said positions for the brush, means mounted on said sill and connected to said movable frame for moving the latter between said positions for the brush, and power means for rotatively driving said brush when it is in the operative position.

8. A snow sweeper railway car embodying therein a wheeled frame including a center sill, an air wedge on said frame and including an upright leading edge arranged substantially centrally of said frame and side surfaces extending rearwardly and outwardly in opposite directions from said edge, an air scoop on said frame and having a horizontal leading edge arranged transversely of the car forwardly of the leading edge of the wedge and below said frame, and including a panel extending upwardly and rearwardly from said edge of the air scoop with upper end portions disposed laterally along each side surface of the air wedge, a cylindrical brush arranged in advance of said edge of the air scoop and having operative and inoperative positions, said brush when in said operative position extending across one of the rails of the track upon which the car may travel, a movable frame in which said brush is journaled for rotation, means connecting said movable frame to said frame for movement between said positions of the brush, means for imparting movement to said movable frame from one to the other of said positions, said

means including a pressure fluid cylinder mounted on said center sill and a piston and rod movable longitudinally of the cylinder and which rod is connected to the movable frame, and power means for rotatively driving said brush when it is in its operative position.

Certificate of Correction

July 25, 1950

Patent No. 2,516,600

CALVIN W. SHIPLEY ET AL.

It is hereby certified that error appears in the printed specification of the above numbered patent requiring correction as follows:

Column 6, lines 20 and 21, for the word "positions" read *portions*;
and that the said Letters Patent should be read as corrected above, so that the same may conform to the record of the case in the Patent Office.

Signed and sealed this 7th day of November, A. D. 1950.

[SEAL]

THOMAS F. MURPHY,
Assistant Commissioner of Patents.
